UNITED STATES PATENT OFFICE.

CHARLES G. FOLSOM, OF SOUTH BEND, INDIANA.

LETTER-BOX.

SPECIFICATION forming part of Letters Patent No. 655,898, dated August 14, 1900.

Application filed March 16, 1900. Serial No. 8,886. (No model.)

To all whom it may concern:

Be it known that I, CHARLES G. FOLSOM, a citizen of the United States, residing at South Bend, in the county of St. Joseph and State 5 of Indiana, have invented certain new and useful Improvements in Letter-Boxes; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to mail-boxes adapted for street use; and its object is to provide a simple and inexpensive box which may be readily opened and closed.

The construction of the improvement will 20 be fully described hereinafter in connection with the accompanying drawings and its novel features defined in the appended claims.

In the drawings, Figure 1 is a view in perspective of a mail-box embodying my invention in closed position. Fig. 2 is a similar 25 view with the door or cover open, and Fig. 3 is a detail perspective view of the door of the box.

The reference - numeral 1 designates the 30 body of the box, which is preferably formed from a single piece of metal bent to U shape. The bottom 2 of the box has its edges turned down at right angles to form flanges 3, which rest against and are riveted to the ends of the 35 body 1. This construction adapts the box to fit upon a square supporting-post, the depending parallel flanges being secured to the post by nails or like fastenings.

One end of the box is closed by an end wall 40 4, and the opposite end is partially closed by an end piece 5. The space below the end 5 is closed by a pivotally-secured door of novel form, as shown in Fig. 3, comprising a plate 6, having its ends bent at right angles to form 45 parallel ears 7, by means of which the door is secured to the box, a pivot-rod 8, secured in bearings in the cover, serving as the pivotal support. The lower end of the cover-plate 6 is formed with a slot 9, through which projects the end of a tongue 10, secured to the 50 under side of the bottom of the box and provided with an opening 11, adapted to receive

a padlock or like fastening for locking the door of the box. As there is at no time any weight to be borne by the door, it will be seen 55 that the frictional engagement of the ears 7 with the body portion will be sufficient to hold the door in any position it may assume. This enables the door to be of light construction and cheaply made. 60

A suitable slot 12 is provided, as shown by dotted lines in Fig. 2, for the insertion of letters or other mail-matter.

It is designed to construct the box of sheet metal, and it will be apparent from the foregoing description, in connection with the drawings, that it may be manufactured economically, the body thereof consisting of a single piece of metal bent to the required shape. 70

The frictional engagement of the ears of the door with the sides of the box is an important characteristic feature of the invention, since by this means the door is maintained in open position to permit the contents 75 of the box to be removed.

As shown in Fig. 2, the door 6 is pivotally mounted at a point intermediate the ends of its ears, so that a portion of said door operates entirely within the interior of the box. 80 This serves, while the door is being opened, to force any of the contents of the box which may be located in the path of movement of the door toward the bottom of the box and into a position where it can be readily removed by the carrier. In addition to this, however, the particular manner of mounting the door serves an important purpose. As shown, the door has its pivot-point near the upper portion of the opening. This causes 90 the outer end of the door to move upwardly, so that when in its open position it projects outwardly above the opening and forms a projecting cover for said opening. The advantages of this construction lie in the fact that 95 in removing the contents of the box, especially during inclement weather, said contents are kept dry, the carrier being able to perform the necessary work entirely under cover of the door and its ears in an obvious 100 manner.

I claim—

1. A mail-box comprising a body portion; a bottom; end walls, one of said walls having

an opening for the removal of the contents; and a door for said opening, pivotally connected to said body portion and having parallel ears frictionally engaging the inner sides 5 of the box, said frictional engagement holding the door in the positions in which it may be placed, said door forming a projecting cover above said opening when in open position.

2. A mail-box comprising a body portion; 10 a bottom; end walls, one of said walls having an opening for the removal of the contents; and a door for said openings, having parallel ears pivotally secured to said body portion, and frictionally engaging the inner sides of 15 the box for holding the door in the positions in which it may be placed, the pivotal connection being intermediate the ends of said ears, the outer portion of said door forming a projecting cover above said opening when in 20 open position.

3. A mail-box comprising a body portion; a bottom; end walls, one of said walls having an opening for the removal of the contents; and a door for said openings, having parallel 25 ears pivotally secured to said body portion, and frictionally engaging the inner sides of the box for holding the door in the positions in which it may be placed, the pivotal connection being intermediate the ends of said 30 ears, said door having a portion of its length

operating solely within the box, the outer portion of said door forming a projecting cover above said opening when in open position.

4. A mail-box comprising a body portion; a bottom therefor, said bottom being of less 35 length than the body portion, to form a recess at one end thereof; an end wall closing one end of the box, said wall extending downward from the top of the body portion to a point intermediate the top and bottom whereby an opening will be formed leading into the box near its bottom and a door having parallel ears frictionally engaging the sides of the box, said frictional engagement holding the door in the positions in which it may 40 be placed pivotally mounted to normally close said opening, the pivotal connection being at a point intermediate the ends of the ears, said door being of greater length than the opening closed thereby, the inner portion operating solely within the box, said door forming a projecting cover above said opening when in open position.

In testimony whereof I affix my signature in presence of two witnesses.

CHARLES G. FOLSOM.
